UNITED STATES PATENT OFFICE.

ROBERT HEAD, OF NEW YORK, N. Y., ASSIGNOR TO THE AEOLIAN COMPANY, A CORPORATION OF CONNECTICUT.

REPEAT DEVICE FOR AUTOMATIC PIANOS AND THE LIKE.

1,402,230.

Specification of Letters Patent.

Patented Jan. 3, 1922.

Application filed July 31, 1918. Serial No. 247,542.

To all whom it may concern:

Be it known that I, ROBERT HEAD, citizen of United States, residing at 558 West 164th Street, New York City, N. Y., have invented new and useful Improvements in Repeat Devices for Automatic Pianos and the like, of which the following is a specification.

My present invention relates to improvements in rewind and repeat devices for player-pianos and other automatic instruments using a music roll. Further the device is adapted to be set for any selected number of repeats and the instrument will then play the roll that number of times and stop.

The drawings illustrate one of the preferred embodiments my invention is adapted to take; and in them Fig. 1 is a front elevation of the music roll box and adjacent motor portion of a player-piano embodying my present invention. The remaining views are on an enlarged scale as compared with Fig. 1. In them, Figs. 2, 3 and 4 are respectively vertical sections partly in elevation on the lines 2—2, 3—3 and 4—4 in Fig. 1 looking in the direction of the arrows; Fig. 5 is a horizontal section partly in plan on the line 5—5 in Fig. 1; Fig. 6 is a horizontal section partly in plan on the line 6—6 in Fig. 2; Fig. 7 is a diagrammatic perspective view of parts taken from Fig. 1 pertaining to my invention; and Figs. 8 to 10 inclusive are diagrammatic face views (looking from left to right) of the same parts shown in successively different operating positions explained later, certain parts in these figures being displaced along the line 18^a for clearness in the illustration.

Describing now the illustrated embodiment of my invention:—1 is the music-roll box of a player-piano; 2 and 2^a are respectively the music-roll and take-up spool operatively supported in the usual manner in the box 1. 3 is the pneumatic-motor whose drive-shaft 4 is chain and sprocket connected (Fig. 1) to the usual clutch-shaft 5. This carries the usual slidable clutch-gear 6 splined to the shaft and the sprocket wheel 7 loose on the shaft. 8 is the usual clutch-lever pivotally supported

at 9 and operable from the key-slip in well-known manner to shift the gear 6 to the left into the position shown in Fig. 1 into mesh with the gear 10 on the driving spindle 11 of the take-up spool to driving the music-sheet 2^b in playing direction downwardly across the tracker-board 12. Reversely, the said lever 8 is operable to shift the gear 6 to the right out of mesh with the said gear 10 and into clutch with the aforesaid loose sprocket-wheel 7 through the usual clutch-pins 14 with the result that the motor then drives the music-roll (instead of the take-up spool) through the chain 15 and sprocket-wheel 16 on the music-roll spindle 17 to rewind the music-sheet back on to the music-roll.

The air-tension for driving the motor 3 and also for operating the sounding-devices is derived in well-known manner from ex- 70 hausters (not shown) driven by an electric-motor (not shown) controlled by an electric switch 18 mounted as shown in Fig. 1 to the right of the piano-casing. This switch has an operating plunger 18^a projecting 75 through a guide-hole in the cheek 1^a of music-box and within said box is provided with a knob 18^b. When this knob and plunger are pulled to the left in Fig. 1 an electric circuit is made through the aforesaid switch 18 to drive the electric-motor to pneumatically drive the motor 3 and otherwise play the instrument; vice versa pushing the knobbed plunger to the right breaks the circuit through the switch and 85 stops the operation of the music-sheet and the playing of the piano.

19 is a crank-arm projecting from the plunger 18^a which plunger by the way is free to turn about its own axis without interfering with its aforesaid switch-operating function. For this and the following part of the description see especially Figs. 3, 5 and 7 in connection with Fig. 1. 20 is a pin projecting from the arm 19 parallel 90 with 18^a; and 21 is a link connecting the arm 19 with a shoe or rider 22 yieldingly held against the periphery of the disc 23 by means of a coiled tension spring 24 pulling said shoe towards the hub of said disc 100

23, which latter is fixed on the music-roll spindle 17.

When the music-roll is being played, the parts are positioned as in Fig. 1 (and the related Figs. 3, 5 and 7) with the disc 23 turning in the direction of the arrow in Fig. 7, and frictionally carrying the shoe 22 and crank-arm 19 into the position shown in said figures,—beyond which position, however, they cannot go (although the disc 23 keeps on turning) because a part 29 on the plunger 18^a abuts against a stop 25 (Figs. 4 and 7, etc.). This stop is a projecting tooth on the underside of a member 26 pivoted at 26^a to the movable board 27 of the bellows 28 so as to pivot freely in a vertical plane, the free end of said pivoted member 26 resting by gravity upon the part 29 secured rigidly to the plunger 18^a in off-set parallel relation thereto.

During the rewind of the music-sheet back on to the music-spool, the disc 23 because it is carried by the music-roll spindle 17 now rotates in the direction of the arrow in Fig. 8, namely, opposite to its direction in Fig. 7. This carries the shoe 22 and crank-arm 19 to the left until stopped in the position shown in Fig. 8 by the pin 20 (cf. Figs. 5 and 7) on the arm 19 striking against the periphery of a repeat-counting disc 30. This disc is fixedly secured to a rod 31 suitably supported to be rotatably adjusted or twisted about its own axis, one end of said rod projecting through the right cheek 1^a of the music-roll box wherein there is a pointer 32 which rigidly projects from the rod and plays over a stationary dial 33 secured to the cheek 1^a. A knob 34 on the end of this rod 31 permits it to be twisted to carry the pointer into registry with the various marks on the dial, which it will be seen is marked "Repeat" coupled with a series of numbers indicating the number of repeats. When the pointer is adjusted to one of the numbers, the mechanism automatically plays and rewinds the music-roll that number of times and then stops the instrument. When the pointer is directed to that part of the dial marked "Continuous," the device automatically repeats the roll indefinitely until the instrument is manually stopped.

The counting-disc 30 performs its function of automatically counting the number of repeats and then stopping the instrument by being provided with ratchet-teeth at 35 and with a cut-away portion or recess at 36. The ratchet 37 may consist of a piece of light spring-wire bent into the shape best shown in Figs. 5 and 7 and secured to the arm 19 by a pin 38. The teeth 35 correspond with the numbers on the dial and are so placed that every stroke of the arm 19 towards the counting-disc 30 (which it will be remembered takes place on the rewind) causes the

ratchet 37 to rotate the disc 30 and the pointer 32 to the next lower number on the dial until the pointer reaches the zero mark whereupon the recess 36 is brought around into a position wherein the pin 20 on the arm 19 enters down into the recess instead of striking against the periphery of the counting-disc 30 as theretofore. As will subsequently appear,—this entry of the pin 20 into the recess 36 determines that this will be the last rewind and that on its completion the instrument will automatically stop.

From the description thus far it will be noted that three positions have been described for the crank-arm 19 which may be conveniently designated A, B and C. The A position is best shown in Fig. 7 (although also shown in Figs. 1 to 5 inclusive and in Fig. 9) and always exists when the music-sheet is traveling in playing direction with the disc 23 carrying the shoe 22 and the arm 19 forward until further rotation of the switch-plunger 18^a about its own axis is stopped by the offset 29 hitting against the stop 25. The degree of upward swing of the aforesaid off-set 29 determined by the A position of the arm 19, also determines the degree of upward lift of the pivoted member 26 so that said member has the position shown in Fig. 7, this being its highest position conveniently designated A because corresponding to the A position of the arm 19. The "A" at the right of Fig. 7 serves to recall these facts.

On every rewind of the music-roll except the last rewind, it will be remembered that the incidental rotation of the disc 23 is such that the shoe 22 and arm 19 are carried rearwardly until the pin 20 on the arm strikes against the periphery of the counting-disc 30. This position of said arm persists during the rewind and may be called its B position. It results in a corresponding, partial rotation of the switch-plunger 18^a and a corresponding, downward swing of the off-set 29 and of the pivoted member 26 resting on said off-set. The letter "B" adjacent Fig. 8 conveniently designates this second or B position of all these parts.

Finally on the last rewind prior to the automatic stopping of the instrument, it will be recalled that the incidental rotation of the disc 23 carries the shoe 22 and arm 19 rearwardly, just as before, but this time the pin 20 on the arm enters the recess 36 in the counting-disc 30, so that this time the arm 19 swings through a greater angle into a new or third position which is shown in Fig. 10 and is conveniently designated its C position. This causes both the off-set 29 and the supported member 26 to be lowered into new or C positions which are lower than their B position.

It will be remembered that the aforesaid

pivoted member 26 is carried by or with the movable board 27 of the bellows 28; and it is in three positions, A, B and C, of this member 26 that are important in the 5 cluding description of the device. Ultimately the operative pneumatic connections to the bellows 28 will be described; but for the present it is sufficient to state that this bellows is momentarily collapsed automatically from the music-sheet at the end of each 10 playing and at the end of each rewind.

The member 26 in its A position with the bellows expanded is located in front of the bent-over upper-end of the lever 40 pivotally 15 supported at 41 and operatively connected by the link 42 to the clutch-lever 8. When the parts are in their assumed A position, it will be noted that the music-roll is being played. When now at the end of the play- 20 ing, a special perforation in the music-sheet momentarily collapses the bellows 28, the movable board of the latter carries the afore- said member 26 against the upper-end of the said lever 40, swinging its lower end to the 25 left in Fig. 1 to operate the clutch to disconnect the motor 3 from the take-up spool 2^a and instead connect it with the music- roll 2 so that the played music-roll is now automatically rewound.

30 Next another lever 43 is provided pivotally supported at 41 with its bent-over upper-end in the path of the member 26 when in its B position (cf. Fig. 8). This lever 43 is operatively connected as shown in Fig. 35 1 by a link 44 to the clutch-lever 8. When the upper end of the previously described lever 40 has been pressed to the right in Fig. 1 by the bellows to bring the pins 14-14 into clutch, and is left in that pos- 40 ition to produce a rewind as heretofore explained,—the effect on the lever 43 is that the link 44 automatically pulls its upper end to left in Fig. 1 into a position immediately in back of the B position of the pivoted member 26 on the bellows ready to be 45 pushed to the right (viz., into the position shown for it at 43 in Fig. 1) by the next collapse of the bellows to operate the clutch-lever 8 into the position shown in Fig. 1 in order to drive the take-up spool once more 50 from the motor to replay the music-sheet.

In its lowest or C position (Fig. 10), the end of the pivoted member 26 is located immediately to the left of a fixed collar 45 55 on the switch-operating plunger 18^a (cf. Figs. 1, 7 and 10). It will be remembered that the C position occurs on the rewind, therefore when toward the end of the rewind the music-sheet momentarily collapses the bellows 28, the latter carries the member 26 against the aforesaid collar 45, pushing the plunger 18^a to the right in Fig. 1 and operating the switch to disconnect the previously 60 described electric motor and thereby auto-

matically stop the further performance of the instrument, this movement of the plunger 18^a being insufficient to disengage the ratchet 37 from the disk 30.

The diagrams, Figs. 7 to 10 inclusive consecutively show the relative position of the parts when the operator has adjusted the pointer 32 on the dial 33 for two repeats. This sets the device so that it will automatically play the selection twice and then stop the instrument after the second re- 75 wind of the music-sheet. Fig. 7 indicates the position of the parts during the first playing of the sheet. Fig. 1 and the sectional figures belonging to it also show the parts as positioned during this first play- 80 ing of the sheet. The pneumatic-motor 3 is driving the take-up spool 2^a through the clutch 6, and the resulting rotation of the music-roll spindle 17 and the disk 23 has brought the parts including the pivoted 85 member 26 into their A position. (Fig. 7.)

At the end of the first playing, the music-sheet automatically collapses the bellows 28 for a moment and the member 26 striking against the lever 40 reverses the clutch so 90 that the drive from the motor 3 is now through the pins 14-14 upon the music-roll spool to rewind the sheet. This is the first rewind and the reversed rotation of the disk 23 puts the parts in their B position as in 95 Fig. 8. Also note that the ratchet 37 on the arm 19 in going into its B position has rotated the counting-disk 30 and the pointer 32 until the latter now points to the numeral "1" on the fixed dial 33. In other words, 100 one playing has been counted off and the recess 36 in the counting-disk has been advanced that much nearer the C or automatic stopping position shown in Fig. 10.

The aforesaid first rewinding continues 105 with the parts as in Fig. 8 until means (hereafter to be described) at or towards the beginning of the sheet automatically collapses the bellows 28 for a moment, whereupon the member 26 operates the lever 43 110 to return the clutch 6 to its original condition wherein the motor 3 drives the take-up spool and the sheet is thereby started on its second playing. This second playing, 115 in view of the explanation in connection with Fig. 7, returns the parts to the A position shown in Fig. 9.

This second playing continues until the bellows-operating end-perforation of the sheet is reached, whereupon said bellows 120 again momentarily collapses, and the member 26 being in its A position, again operates the lever 40 to start the second rewinding of the music-sheet. This of course immediately reverses the rotation of the music- 125 roll spindle 17 and disc 23, so that the arm 19 and ratchet 37 carry the counting-disk 30 and pointed 32 to zero on the dial with

the recess 36 positioned so that it receives the pin 20 on the arm 19, whereby the parts, including the member 26, are carried into their C position shown in Fig. 10. The 5 automatic collapse of the bellows 28 at the end of this second rewind, carries the part 26 against the shoulder 45 on the switch-operating plunger and thereby automatically "throws" the switch to stop the instrument.

10 The drawings show the device designed for a maximum of three automatic repeats (followed by a cut-off or stop) but the number can obviously be increased. For example, to increase the number to 6, it is 15 only necessary to proportion the parts so that the throw of the ratchet 37 on each rewind will be only one-half that shown, whereby the counting-disc 30 is only rotated one-half its present rotation, six ratchet- 20 teeth being then used on said counting-disc spaced only half as far apart as those shown. This and other ways to increase the number of automatic repeats will obviously suggest themselves—but the three shown will 25 ordinarily be sufficient in practice.

When the pointer 32 is turned so as to point to "continuous" on the dial, then the device causes the instrument to repeat the roll indefinitely until manually stopped. 30 This is because the teeth 35 on the counting-disc 30 are then placed out of the reach of the ratchet 37 so that the latter now slides idly on the periphery of the disc 30 without turning it and the pin 20 at every rewind 35 abuts against the periphery of said disc and never enters the recess 36 to put the parts into the C position to throw the switch.

The particular means may vary for automatically operating the bellows 28 at or towards the end of each "playing" and "rewinding" of the music-sheet or part thereof. In the drawings I show for operating the bellows at the end of each "playing," a tracker-duct 46, Fig. 1, connected by tubing 47 as usual in the art to a valve-box 48 which in turn is connected, as shown, to the exhaust by tube 49 and to the bellows 28 by tube 50. The tracker-duct 46 is kept closed by the music-sheet until the place is reached 45 during the playing where it is desired for the playing to stop and the rewinding to commence. At this place a perforation 51 is provided in the sheet, (although of course in practice it will ordinarily not be located 50 so near the beginning of the sheet) which, when it registers with tracker-duct 46, operates the valve 48 in well-known manner to connect the exhaust with the bellows 28, thereby collapsing it and effecting rewind 55 of sheet as previously described, said rewind of course immediately closing the duct 46 so that the valve then connects the bellows with the atmosphere causing it to expand.

Finally, I will describe the illustrated 65 novel means for automatically stopping the rewind at the beginning of the sheet and starting the replaying without using a special perforation in the music-sheet for this purpose, although of course this might be 70 done as an alternative method. However, I have preferred to show the following devices for this purpose:—52 is a tubular elbow stationarily mounted in the music-roll box at the right end of the take-up spool 2^a. 75 The mouth of the vertical branch of this elbow constitutes a port which is kept normally closed by a spring-pressed valve 53 pivotally supported at 54 and having a lug 55 extending laterally from its rear end towards the hollow existing in the right-hand end of the take-up spool. The horizontal branch of the elbow is operatively connected by a piece of tubing 56 leading under the pouch in the valve-box 48 in the same way 80 that the tube 47 connects the tracker-duct 46 thereto. Located circumferentially within the hollow-end of the take-up spool is a curved metal strip 57 fixedly secured in 85 said position by detents, one of which is 90 shown at 57^a. This strip may be about 270° long, as shown in Fig. 2. Located in the space between the ends of the fixed strip 57 is another strip 57^b which is radially movable relatively to the take-up spool and 95 strip 57. This strip 57^b has one end located adjacent one end of the strip 57 as in Fig. 2; and its opposite end is bent outwardly and then extends circumferentially 100 as shown in said Fig. 2. The radial movement of this strip 57^b is provided for by its being fixed on a radially slidable pin 58 between the enlarged head of said pin and 105 a light coiled compression spring 59 surrounding the shank of the pin. The pin 58 in turn is supported for its said radial slid- 110 able movement in suitable bearing-openings provided respectively in the outer-shell and in the hub of the take-up spool adjacent the right-hand flange (cf. Fig. 1) of the spool, 115 so that the head of the pin when engaged by the face of the music-sheet will be pressed into the take-up spool flush with its periphery. Also, at such time the part 57^b will be 120 carried radially inward along with the pin into a position wherein it will pass freely under the described lug 55 of the valve when the take-up spool is rotated. This is the normal condition as long as the face of the music-sheet covers the head of the pin 125 58; and persists throughout except, when towards the end of the "rewind," the pointed front-end of the sheet is reached at the take-up spool as in Figs. 1, 2 and 6, whereby the sheet no longer covers and presses inwardly the pin 58 and the part 57^b. At this time, the part 57^b springs into 130 its outward position of Fig. 2 and its

bent forward end passes over the top of the lug 55 and cams it down so that said lug passes inside the strip 57 whereby the valve 53 is lifted off its port for a sufficient interval to operate the valve-box 48 and in turn collapse the bellows 28 to reverse the clutch-lever 8 (Fig. 1) to start replaying the sheet before it can detach itself from the hook of the take-up spool. Immediately 10 the replaying begins, the sheet winding on the take-up spool again covers and presses inwardly the pin 58 carrying with it the part 57^b so that said end during the rotations of the take-up spool passes freely below the valve-lug 55 without disturbing the normal closed position of the valve on its port.

Of course changes can be made, additional to those already indicated, in the illustrated 20 embodiment of my invention without departing from the spirit of said invention and of the annexed claims.

What I claim is:

1. In combination with the music-roll, 25 take-up spool, motor and reversing means of an automatic musical instrument, the music-sheet having a narrowed front end,—a pneumatic for operating said reversing means; a port and valve therefor controlling said 30 pneumatic; a movable part carried by the take-up spool toward one end having an inner position when it is covered and pressed inwardly by the music-sheet, and an outer position when it is not covered by the music- 35 sheet and is released, said movable part being operatively related to the valve.

2. In combination with the music-roll, take-up spool, motor and reversing means 40 of an automatic musical instrument, the music-sheet having a narrowed front end,—a movable part carried by the take-up spool toward one end having an inner position when it is covered and pressed inwardly by the music-sheet, and an outer position when 45 it is not covered by the music-sheet and is released, said movable part being operatively related to the reversing means.

3. In combination with the pair of spools 50 and the music-sheet operatively related thereto in an automatic musical instrument, the music-sheet comprising a narrowed portion,—a controllable means; and a movable part carried by one of said spools having an inner position when it is covered and 55 pressed inwardly by the music-sheet, and an outer position when it is not covered by the music-sheet and is released, said movable part being related to said controllable means to control its operation.

60 4. In combination with the pair of spools and the music-sheet operatively related thereto in an automatic musical instrument, the music-sheet comprising a narrowed portion,—rewinding means; and a movable part

assuming one position when the narrowed portion of the music-sheet is adjacent to it and another position when at the unnarrowed part of the music-sheet, said movable part being related to said rewinding means to control its operation, and repeating means 70 capable of being set manually for different numbers of repeats.

5. In combination with the motor, reversing means, pair of spools and the music-sheet operatively related thereto in an automatic musical instrument, the music-sheet comprising a narrowed portion,—a movable part assuming one position when the narrowed portion of the music-sheet is adjacent to it and another position when at the unnarrowed part of the music-sheet, said movable part being operatively related to the reversing means to control its operation, and repeating means capable of being set manually for different numbers of repeats.

6. In combination with the music-roll, take-up spool, motor, motor cut-off, and reversing means of an automatic musical instrument, a rotary part partaking of the motion of the music-roll in playing and rewinding; a rider carried with the rotary part in either direction until stopped when it slips thereon; a crank-arm reciprocated by the rider; a stop for the crank-arm after it has been swung a limited distance into one position by the rider during playing, a recessed rotatable disc whose periphery where unrecessed stops the crank-arm in a second position when the crank arm is swung by the rider in rewinding, and where recessed, allows it to assume a third position; means which gives the disc a fraction of a rotation for each rewinding swing of the crank-arm until it reaches the recessed portion of the disc; manual means for preliminarily setting the disc for a selected number of repeats; a power-element controlled from the music-sheet so as to be operated at predetermined times relatively to such sheet; a member which is adjustable into three different positions by the crank-arm in assuming its three respective positions aforesaid, said power-element and member being operatively related to the reversing means and motor cut-off to operate the reversing 105 means to effect rewinding when the adjustable member is in its first position referred to and to effect playing when the member is in its second position, and to operate the motor cut-off when the member is in its 110 third position.

7. In combination with the music-roll, take-up spool, motor, motor cut-off, and reversing means of an automatic musical instrument,—a rotary part partaking of the motion of the music-roll and take-up spool in playing and rewinding; means carried with the rotary part in either direction until

stopped whereupon said means slips on the rotary part; a stop and a recessed rotatable disc forming end limits to said movements of the carried means and whereby it is adapted to assume three different positions; means for giving the disc fractional, rotary movements in the same direction from the movements of the carried means until the latter reaches the recessed portion of the disc; 10 manual means for preliminarily setting the disc for a selected number of repeats; means controlled from the music-sheet so as to be operated at predetermined times relatively to such music roll, said means being operatively related to the reversing means and the motor cut-off through the aforesaid carried means so that when the latter is in one position, the reversing means is operated to effect rewinding; when in a second position, 15 the reversing means is operated to effect playing; and when in a third position the motor cut-off is operated.

8. In combination with the music-roll, take-up spool, motor, motor cut-off, and reversing means of an automatic musical instrument, a rotary part partaking of the motion of the music-roll and take-up spool in playing and rewinding; means carried with the rotary part in either direction until 20 stopped; a stop and a recessed movable part forming end limits to said movements of the carried means and whereby it assumes three different positions; means for giving the recessed part increments of movement in the same direction from the movements of the carried means until the latter reaches the recess of said part; manual means for preliminarily setting the recessed part for a selected number of repeats; means controlled 25 from the music-sheet so as to be operated at predetermined times relatively to said music roll, said means being operatively related to the reversing means and the motor cut-off through the aforesaid carried means so that 30 when the latter is in one position, the reversing means is operated to effect rewinding; when in a second position, the reversing means is operated to effect playing, and when in a third position the motor cut-off 35 is operated.

9. In combination with the music-sheet, motor, motor cut-off, and reversing means of an automatic musical instrument, means carried in one direction in playing the music-sheet and in the opposite direction in rewinding it; stops forming end limits to said movements of the carried means, one of said stops being movable and having an upper and a lower level in its active face, 40 so that the two stops permit the carried means to assume three different positions; means for feeding the movable stop in one direction from the movements of the carried means until a different level in the face of

the stop is presented to the carried means; 45 manual means for preliminarily setting the movable stop for a selected number of repeats; means controlled from the music-sheet so as to be operated at predetermined times relatively to such sheet, said means being operatively related to the reversing means and the motor cut-off through the aforesaid carried means so that when the latter is in one of its positions, the reversing means is operated to effect rewinding; when 50 in another position, the reversing means is operated to effect playing; and when in a third position the motor cut-off is operated.

10. In combination with the music-sheet, 55 motor, motor cut-off, and reversing means of an automatic musical instrument, means carried in one direction in playing the music-sheet and in the opposite direction in rewinding it; stops forming end limits to said movements of the carried means; means controlled from the music-sheet so as to be operated at predetermined times relatively to said sheet, said means being operatively related to the reversing means through the aforesaid carried means so that when the latter is stopped in one of its positions, the reversing means is operated to effect rewinding; and when it is stopped in its other position, the reversing means is operated to effect playing.

11. In combination with the music-sheet, 60 motor, motor cut-off, and reversing means of an automatic musical instrument, means carried in one direction in playing the music-sheet and in the opposite direction in rewinding it; stops forming end limits to said movements of the carried means; a power-element controlled from the music-sheet so as to be operated at predetermined times relatively to said sheet; a member 65 which is adjustable into different positions by the aforesaid carried means corresponding to the different positions of said means, said power-element and member being operatively related to the reversing means 70 to effect rewinding when the adjustable member is in one of its positions and to effect playing when in its other position.

12. In combination with the music-sheet, 75 motor, motor cut-off, and reversing means of an automatic musical instrument, means carried in one direction in playing the music-sheet and in the opposite direction in rewinding it; stops forming end limits to said movements of the carried means; means controlled from the music-sheet so as to be operated at predetermined times relatively to said sheet, said means being operatively related to the reversing means through the aforesaid carried means so that 80 when the latter is stopped in one of its positions, the reversing means is operated to effect rewinding; and when it is stopped in 85

its other position, the reversing means is operated to effect playing; and means which automatically counts the number of repeats and which, after the desired number has occurred, withdraws one of the stops, permitting the carried means to assume a third position leading to the operation of the motor cut-off.

13. In combination with the music-sheet, 10 motor, motor cut-off, and reversing means of an automatic musical instrument, means carried in one direction in playing the music-sheet and in the opposite direction in rewinding it; stops forming end limits of 15 said movements of the carried means; a power-element controlled from the music-sheet so as to be operated at predetermined times relatively to said sheet; a member which is adjustable into different positions 20 by the aforesaid carried means corresponding to the different positions of said means, said power-element and member being operatively related to the reversing means to effect rewinding when the adjustable 25 member is in one of its positions, and to effect playing when in its other position; and means which automatically counts the number of repeats and which after the desired number has occurred, withdraws one 30 of the stops to permit both the carried means and the adjustable member to assume third positions respectively, whereby the latter actuates the motor cut-off when the power-element is operated.

35 14. In combination with the tracker-bar, motor, motor cut-off, reversing means, pair of spools and the music-sheet operatively related thereto in an automatic musical instrument, the music-sheet having a narrowed front end and being perforated at a desired 40 ending place to register with a tracker-bar duct,—means carried in one direction in playing the music-sheet and in the opposite direction in rewinding it; stops forming end 45 limits to said movements of the carried means; a pneumatic operatively related to the reversing means and the motor cut-off through the aforesaid carried means so that when the latter is stopped in one of its 50 positions, the reversing means is operated to effect rewinding and when it is stopped in its other position, the reversing means is operated to effect playing; operative connections between the aforesaid tracker-bar duct 55 and the pneumatic; and a movable part located at the music-sheet take-up spool assuming one position when the narrowed front end of the music-sheet is adjacent to it and another position when at the unnar- 60 rowed body portion of the sheet, said movable part being operatively related to the aforesaid pneumatic to bring about its operation when the movable part is at the nar- rowed front end of the sheet.

15. In combination with the tracker-bar, 65 motor, motor cut-off, reversing means, pair of spools and the music-sheet operatively related thereto in an automatic musical instrument, the music-sheet having a narrowed front end and being perforated at a desired 70 ending place to register with a tracker-bar duct,—means carried in one direction in playing the music-sheet and in the opposite direction in rewinding it; stops forming end limits to said movements of the carried 75 means; a pneumatic operatively related to the reversing means and the motor cut-off through the aforesaid carried means so that when the latter is stopped in one of its positions, the reversing means is operated to 80 effect rewinding and when it is stopped in its other position, the reversing means is operated to effect playing; operative connections between the aforesaid tracker-bar duct and the pneumatic; a movable part located 85 at the music-sheet take-up spool assuming one position when the narrowed front end of the music-sheet is adjacent to it and another position when at the unnarroed body portion of the sheet, said movable part being 90 operatively related to the aforesaid pneumatic to bring about its operation when the movable part is at the narrowed front end of the sheet; and means which automatically counts the number of repeats and which, 95 after the desired number has occurred, withdraws one of the stops, permitting the carried means to assume a third position leading to the operation of the motor cut-off.

16. In an automatic musical instrument, 100 the combination with the motor, the pair of spools, the music sheet operatively related to the spools, and reversing means for causing the music sheet to be advanced and rewound by the motor, of a device controlled 105 by the music sheet for setting the reversing means to rewind such sheet, a device also controlled by the sheet for setting the reversing means to advance the sheet for playing repeats, and means capable of being set 110 manually to determine the different numbers of repeats to be played.

17. In an automatic musical instrument, the combination with the motor, the pair of spools, the music sheet operatively related to 115 the spools, and reversing means for causing the music sheet to be advanced and rewound by the motor, of a device controlled by the music sheet for setting the reversing means to rewind such sheet, a device also controlled 120 by the music sheet for setting the reversing means to advance the music sheet, and selecting means capable of being set to determine the different numbers of repeats to be 125 played, said selecting means governing the action of said device which controls the advance of the music sheet.

18. In an automatic musical instrument,

the combination with the motor, the pair of spools, the music sheet operatively related to the spools, and reversing means for causing the music sheet to be advanced and rewound by the motor, of a device controlled by the music sheet for setting the reversing means to rewind such sheet, a device also controlled by the music sheet for setting the reversing means to advance the sheet for playing repeats, and selecting means capable of being

set to determine the different numbers of repeats to be played and governed by the direction of movement of the music sheet, said selecting means governing the action of the device which controls the advance of the 15 music sheet.

In testimony whereof, I, said ROBERT HEAD, have signed my name to this specification, this thirtieth day of July 1918.

ROBERT HEAD.
